UNITED STATES PATENT OFFICE.

H. HENRY PICKENPACK, OF BROOKLYN, NEW YORK.

RIGGING-STRETCHER.

SPECIFICATION forming part of Letters Patent No. 311,605, dated February 3, 1885.

Application filed October 23, 1884. (No model.)

To all whom it may concern:

Be it known that I, H. HENRY PICKENPACK, of Brooklyn, in the county of Kings and State of New York, have invented a new and useful Improvement in Rigging - Stretchers; and I do hereby declare that the following is a full and exact description thereof, reference being had to the accompanying drawings, and to the letters of reference marked thereon, 10 making a part of this specification.

My invention relates to that class of devices for securing the rigging of vessels in which the end of the shroud is made fast to an extended perforated metallic plate adapted to be inserted between two perforated plates 15 united and made fast to a chain-plate or the side of the vessel, the central plate being confined between the other two by means of belts led through such of the perforations as are brought into register.

Heretofore the proper register of the perforations to admit of the insertion of a retaining-bolt through the three plates has been attained either by the aid of a capstan or windlass or by means of a screw-jack consisting of 25 two heads made to engage the single shroud-plate above and the double plates below, and which are drawn together by means of screws, as may be found described in the Letters Patent to Smith and Fludder, No. 38,919, dated June 16, 1863, while to facilitate the registry 30 of the holes and attain the same with a comparatively slight movement of the central interposed shroud-plate the intervals between the holes have been made longer in the central plate than in the outer plates, as is shown 35 in the English Patent No. 281 of 1854.

The object of my invention is to improve upon these devices, so as to admit of a greater 40 range of movement in the overlapping securing-plates than is possible when a central plate is made to interlock with a forked plate or two outer plates, and to provide thereby for tightening the shroud or rope, so that it may 45 be stretched perfectly taut by the unaided efforts of a man or boy, without the necessity of using a crab or winch or rigging-screws, and without the need of lanyards or turn-buckles, such as are now in use.

50 It consists in the combination, with each other, of two simple overlapping perforated

plates—one made fast to the end of the shroud or rope, and the other hinged to the chain-plate or other fixed stationary support in such manner as to allow the ends of the upper plate, 55 as it slides over the face of the lower plate, to pass over and beyond the ends of said lower plate, the two being prevented from springing apart by a clasp or guide-strap made fast to the one plate to overlap the edges of the superimposed plate. By this means the shroud-plate may be carried down beyond the end of the lower plate, to project over the chain-plate, if need be, so that much shorter plates 60 may be used, which becomes very desirable in view of their rigidity, while all the advantages of a double connecting-plate to receive the shroud-plate are attained in simple form by the strap or straps connecting the two overlapping plates.

It consists, moreover, in the arrangement of the superimposed plates with reference to each other and to a differential series of holes in the two, the upper shroud-plate—which slides over and upon the front or outer face of the lower plate hinged to the chain-plate—being perforated at wider intervals than said lower plate, whereby a pointed bar inserted through one of the holes in the shroud-plate to engage the lower edge of the underlying 75 hole in the lower plate will afford a powerful leverage to force the shroud-plate downward, as hereinafter more fully described.

It consists, also, in the combination, with these devices and with draw-heads connected 80 by screws and adapted to bring the ends of the plates together when wholly separated, so that they may overlap far enough to admit of the insertion of a lever, of a flange formed on the upper end of the upper draw-head, to 85 strengthen the same and steady its hold upon the shroud-plate, as hereinafter described.

In the accompanying drawings, Figure 1 is an elevation in perspective, illustrating a ship's shroud made fast by my invention; Fig. 95 2, a side view of the same; Fig. 3, a longitudinal section illustrating the mode of applying the tightening-levers; Fig. 4, plan views of the two confining-plates detached, illustrating the differential holes therein; Fig. 5, an elevation 100 of the two plates in combination with a screw-coupling adapted for drawing them together

until they overlap, to permit of their engagement by the tightening-levers; and Fig. 6, a side view of the plates provided with a loose slide and adapted to be hooked into eyes in the rope end and in the chain-plate.

A' represent two extended plates, each perforated with a series of holes adapted to come into register when the plates are superimposed one upon the other. One of these plates, A, is connected at one end by a pivotal joint with the chain-plate B on the side of the ship, the joint being formed either by means of an interposed shackle, as represented at C in Figs. 1, 2, and 3, or preferably, and 15 with short plates, by means of a hook, D, (see Fig. 6,) to permit the end of the superimposed plate A to slide freely by and beyond the joint. The second plate, A', is secured at its outer end to the end of the shroud S in any suitable 20 manner—as, for example, by means of a dead-sheave, E, inserted in a fork or bracket, F, at the end of the plate, and around which the rope is led and made fast, as illustrated in Figs. 1, 2, 3, and 4.

25 Although not essential, I prefer to combine with the plates A A' clasps G G, Figs. 1, 2, and 4, secured to the edges of one of the plates to overlap the sides and partially the outer face of the opposite plate, so as to permit a 30 free longitudinal movement of the two and yet retain them face to face, and these clasps may be united in one as a strap fitted to one plate to embrace the other. A loose strap, G', Fig. 6, adapted to slide and fit snugly over the 35 superimposed plates and confine them face to face, may be employed as an equivalent device. When the two plates A A' are brought together and superimposed, so that any two of the holes therein shall register, they may be 40 secured and the rope made fast by means of a bolt, H, led transversely through the two plates. (See Figs. 1, 2, and 6.)

To facilitate the stretching of the shroud, the number of perforations within a given 45 length is made greater in the movable shroud-plate A, which is attached to the rope S, than in the fixed plate A'—as, for example, the plate A may, as is represented in the drawings, be perforated with six holes, and the plate A' 50 with but five, in the same direction; hence, when the plates are superimposed and any two of the holes are in register, as at a, Fig. 3, the remaining holes in the one plate, A, will be partially covered by those in the superimposed plate, A', thus affording an opportunity 55 to obtain a leverage upon the outer plate by means of the fulcrum afforded by the upper edge of one of the holes in the under plate, as at a, Fig. 3, for the end of a lever, K, which 60 is inserted through the corresponding hole, n, in the outer plate. The lever K thus inserted may then be brought to bear on the lower edge of said outer hole, n, as illustrated in Fig. 3 of the drawings. In said Fig. 3 the 65 lever K, which may consist of a marline-spike or any long sharp-pointed iron bar, is rep-

resented as just inserted through the narrow opening formed by the overlapping of the two holes m n, the point of the lever finding a fulcrum or point of support against the upper 70 edge of the hole m in the fixed plate A, and a bearing upon the lower edge of the hole n in the movable plate A', so that by bearing down upon the outer end of the lever a very powerful purchase is obtained upon the plate A', to 75 draw it down over the plate A. The result of this movement is illustrated by the position of the lever K' in the drawings, which is represented as having been drawn down far enough to permit the insertion of the second lever, K, 80 into the holes m n. After the lever K has in turn been forced downward as far as practicable, the lever K' is removed and inserted into the opening, which will thereupon be presented through the holes r s. Thus, with the 85 two levers, the shroud may be gradually tightened and stretched to the utmost with entire ease. When the shroud is properly tightened, it is made fast and held by passing a bolt, H, through the two holes in the plate which may 90 be in perfect register, as at a, Fig. 3.

In the use of the leverage-plates A A' for stretching or tightening up new ropes or wire rigging, in which there is considerable slack to be taken up, the need of very long leverage-plates is avoided by using draw-heads L L' and threaded rods M M (see Fig. 5) for taking up the slack and drawing the plates A A' in position to overlap. The long screw-rods M M are adapted to turn loosely in the lower 95 draw-head, L, and to pass freely through the upper head, L'. The lower draw-head, L, is provided with a central hole, by means whereof it is readily bolted to any one of the apertures in the fixed leverage-plate A. The upper draw-head, L', is constructed with a flange, R, projecting from its upper edge at right angles to its face, and this flange is notched centrally to permit it to embrace the shroud above the grommet or the dead-sheave at the end 100 thereof, and thereby obtain a hold upon the rope, as illustrated in Fig. 5 of the drawings. By screwing up nuts T T upon the ends of the screws M M the draw-heads are drawn together until the plates A A' overlap sufficiently 105 to permit of the insertion of the lever K, as shown in Fig. 6, and the setting up of the shroud is thereupon completed by the use of the levers K K', the draw-heads L L' being 110 detached and removed. Thus, by means of 115 the draw-heads and the leverage-plates, any shroud or rope may be set upon with perfect ease, and all necessary tension thereof obtained by one man alone.

Briefly recapitulated, the advantages of my 125 improvement, in which two simple perforated plates—the one movably secured to the shroud and the other fixed and made fast to a chain-plate or other point of support, and in which the perforations in the movable plate are at 130 wider intervals than those in the fixed plate—are so superimposed as that the movable plate

may not only slide over and upon the underlying fixed plate, but be free to pass beyond the ends of said underlying plate, are, first, that comparatively short plates may be used 5 with all the advantages of the long plates, which are required where a single movable plate is made to pass between two fixed plates; second, that the movable plate may be drawn or set up and the shroud or rope connected thereto be tightened by means of pointed levers, affording a powerful leverage; third, by the use of said levers the confining bolts admit of being more readily and quickly detached to permit a separation of the plates 10 than has heretofore been possible, thereby effecting an important saving of time upon lighters and other boats, where it is required to frequently set free the shrouds and make them fast again in the loading and unloading of the 15 craft.

I claim as my invention—

1. The combination, with a single plate hinged or pivoted to a fixed support, of a second single plate secured to the loose end of a shroud or rope, each plate being provided with a series of bolt-holes, and one of them with a clamping plate or plates projecting from its edges, to overlap the edges of the other when the two plates are superimposed, substantially 25 in the manner and for the purpose herein set forth.
2. The combination, with each other and with the loose end of a shroud or stay-rope 30

and a fixed support for the same, of a single plate attached to the fixed support by a pivotal connection and perforated longitudinally with a series of holes, and a second single plate secured to the end of the shroud or stay-rope to slide over and overlap the ends of the first plate, and which is pierced with a series 35 of holes perforated at greater intervals apart than are those in said first plate, to provide thereby a fulcrum for a lever inserted through one of the outer holes into the underlying hole to move said sliding plate, substantially in the 40 manner and for the purpose herein set forth.

3. In a device for stretching and securing the shrouds of a vessel and other stay-ropes, consisting of a single perforated movable plate secured to the shroud or rope to overlap a second fixed plate secured to the chain-plate or other fixed support, draw-heads adapted to be made fast to the fixed and movable perforated plates, and screws for drawing said heads together, a notched flange, R, projecting from 50 the upper draw-head at a right angle to its face, to strengthen and stay the same, substantially in the manner and for the purpose herein set forth.

In testimony whereof I have signed my name 55 to this specification in the presence of two subscribing witnesses.

H. HENRY PICKENPACK.
